UNITED STATES PATENT OFFICE.

RICHARD H. MONK, OF BROOKLINE, MASSACHUSETTS.

NAPPING MACHINE.

Application filed January 3, 1925. Serial No. 354.

This invention relates to machines for raising the nap on fabrics and although more particularly shown and described hereinafter as embodied in a machine for raising the nap on blankets which have been laundered, yet the invention is capable of application broadly to various types of brushing and combing machines.

After being laundered, blankets dry out into a more or less hard and matted condition and it has been customary to restore the blanket to normal condition by the use of napping machines. In the general type of such machines heretofore in use, the blanket is fed by suitable feed rolls or other means against a rotating brush which raises the nap and returns the blanket to a normal light, fleecy condition. The position of the brush in relation to the work is of prime importance in such machines for if the brush is too close, it cuts into the bodies of the blankets, wearing them out rapidly, and if not close enough, the work has to be done over. At the present time, the position of the brush is regulated by hand-operated adjusting means which have to be constantly adjusted because of the great variation in the thickness of the blankets; all of which consume time and labor and are more or less inaccurate.

The main object of my invention is the provision in a machine of the character described of means for automatically adjusting the position of the napping or brushing roll in relation to the work.

Another object of the invention is the provision of means whereby the napping or brushing roll is automatically adjusted in accordance with the thickness of the work.

A further object is the provision of automatic adjusting means which are capable of being set to determine the depth of penetration in the work of the napping roll and thereby the depth of the raised nap.

Other objects of the invention will be more specifically set forth and described herein-after.

One of the important features of my invention resides in providing a floating roll for raising the nap; that is, a roll which is eccentrically mounted or hung so that it is held against the work by its own weight or by gravity and is free to move to and from the work in accordance with the varying thickness of the work. In the use of a floating

roll, the depth of penetration into the work of the card clothing or bristles may be regulated to some extent by weighting the roll. The use of such a roll obviates the making of adjustments, since the determination of the depth of penetration for any one thickness of work will apply to all thicknesses within practical limits.

Another feature of the invention consists in providing positive means for positioning the roll in relation to the work which is automatically operated by the varying thickness of the work so that after an initial adjustment of the roll in order to produce a certain result no further adjustments are required and in the operation of the machine the roll changes its position to correspond to the thickness of the work. This means may be operated either through the medium of the feed rolls or of any other suitable means.

In the drawings illustrating one form of my invention, Fig. 1 is a plan view of the essential portions of a napping or brushing machine showing brush positioning means constructed and operated in accordance with my invention; Fig. 2 is a side elevation of the same looking from right to left in Fig. 1; Fig. 3 is a central cross-sectional view on line 3—3 in Fig. 1 looking from left to right and on an enlarged scale; and Fig. 4 is a vertical sectional view of the feeding means arranged for automatically regulating the position of the napping roll in accordance with the varying thickness of the work.

In the drawings illustrating the preferred embodiment of my invention, there is shown a machine comprising a floating napping roll, means for feeding work against the roll and means automatically operated by the feeding means for regulating the position of the roll in relation to the work and in accordance with the varying thickness thereof.

In the machine shown 10 designates the upper portion of a table or frame which may be of any form suitable for supporting the operative parts. A brushing or napping roll 12 provided with card clothing or bristles 14 may be secured to a shaft 16 which in turn is rotatably journaled in the lower ends of two hangers 18 and held thereto by end-plates 20 fastened by bolts 22. Each of the hangers 18 may be pivotally secured at its upper end by a pin 24 to the overhanging end 26 of an upright standard or bracket 28.

fastened to the table 10 by bolts 30. Being suspended by the two hangers, the roll 12 swings or floats in so far as it is permitted by the other mechanism.

5 For feeding the work any suitable feeding means may be provided and one such is shown comprising two co-operating feed-rolls 32 and 34, each mounted on a shaft 36, the ends of which are adapted to fit loosely 10 in U-shape end-plates 38 which may be bolted in an upright position to the frame 10 by bolts 40 passing through flanges 42. The lower feed-roll 32 is fixed, since the ends of its shaft 36 rest in the lower ends of the 15 channels 44 in end-plates 38, but the upper feed-roll 34 is free to move vertically to accommodate work of varying thickness. Two gears 46 may be mounted on the ends of the two shafts 36 on one side of the machine 20 and locked thereon by keys 48, the two gears enmeshing to drive the feed-rolls in unison.

In front of the feed-rolls may be arranged any suitable mechanism for delivering the work in flat unwrinkled condition to the 25 feed-rolls, such as a plurality of endless tapes 50 stretched over and between shafts 52 and 54, either one of which may be driven by any suitable means to cause said tapes to travel toward the feed-rolls and to carry the 30 work thereon. The said shafts may be rotatably supported by a frame 56 fastened to the frame 10 by bolts 58.

Between the feed-rolls and the napping roll may be arranged an idler roll 60 over 35 which the work is fed and which serves to hold the work as it is operated upon by the napping roll. Any suitable form of support may be used for this purpose, however, which will hold the work against withdrawal away from the roll.

40 Although it is possible to use the force of gravity alone for keeping the napping roll 12 in engagement with the work by mounting it off center as shown in Figs. 2 and 3 of the drawings, yet preferably, I provide positive means for regulating the position of the roll in relation to the work and one form of such means consists of a wedge-shaped block 70 adapted to be inserted at 45 each end of the roll 12 between it and a fixed support 72 to limit the movement of the roll toward the work. Any suitable means may be provided for operating the two blocks 70 in accordance with the varying thickness 50 of the work, but preferably this result may be accomplished by utilizing the feed-rolls in the following manner. Each end-plate 38 is provided with a top-plate 71 secured thereto by bolts 73 and having on its top 55 surface an upright lug 74 to which is pivotally connected by a pin 75 a lever 76. The short arm of the lever 76 is normally in engagement with a vertical pin 77 which passes loosely through the top-plate 71 and rests 60 upon a bearing block 78 supported on the 65

shaft 36 of the upper feed-roll 34. The long arm of the lever 76 loosely engages and encircles a pin 80 which is screwed into the wedge-block 70, and the pin is provided with an annular flange 81 engaging the under side of the long arm of the lever 76 so that the downward movement of the long arm drives the pin 80 and block 70 downwardly. The upper end of the pin 80 may be grooved to receive the end of a screw driver or other instrument to permit an adjustment of the block 70, and position of the roll 12. A spring 83 having its lower end nested in a recess 84 formed in the base of the bracket 28 and its other end encircling a depending central lug 85 formed on the under side of the block 70 serves to hold the block upwardly with the flange 81 in engagement with the long arm of the lever 76 and the short arm pressing the pin 77 down upon the bearing block 78.

Any form of fixed support 72 may be utilized and the form shown is one secured to the end-plate 38 by a double-shanked screw 87 and having an oblique face 88 provided with a tongue 89 adapted to engage a corresponding groove in the block 70 to prevent lateral movement thereof. On its opposite side, the block 70 engages the lower end of the hanger 18.

55 In order to prevent any twisting or warping of the napping roll in its relation to the work, the foregoing means may be preferably arranged at each end of the roll and the two units work in unison.

For the purpose of holding the hangers in engagement with the wedge-blocks 70 at all times, and therefore the napping roll in its proper position in relation to the work, each hanger 18 may be provided with a rearwardly extending fixed arm 90 on the end of which may be hung a weight receiving element 92 adapted to receive weights 93. The aggregate weights applied at these points may be varied in accordance with the results 105 sought.

60 For driving the machine, the shaft 16 may be extended and provided with a pulley 100 and an idler 102 connected to any suitable source of power by a belt 104 and the other end of the shaft may be provided with a pulley 106 to receive a belt or chain for driving the feed-rolls and tapes 50. The latter means are not shown since they are well known.

65 In the operation of the machine, the floating roll is first adjusted for normal position in relation to the work. This adjustment is made by turning the pin 80 to raise or lower the wedge-block 70 which moves 125 the floating roll toward or away from the work and thereby determines the depth of the nap to be raised. So long as the depth of nap desired remains constant no further adjustment is required since the position of 130

the floating roll is automatically changed to correspond with the thickness of the work.

After the normal position of the floating roll has been determined, the work may then be passed through the machine. It is laid out in flat form and stretched upon the tapes 50, which carry it forward to the feed rolls which feed it forward over the idler roll where the card clothing of the napping roll comes in contact with it and brushes it in the same direction as it is fed. In this position, the weights 93 on the fixed arm 90 hold the napping roll in engagement with the wedge-block, which regulates the depth that the card clothing penetrates the fabric; the weights preventing any retractive action of the roll due to the resistance offered to the card clothing by the work. After the nap is raised, the work passes downwardly into a proper receptacle. In treating blankets, it is customary to run the work through the machine twice, presenting first one side and then the other.

After the adjustment has been made, if thicker work is inserted between the feed-rolls, the upper feed-roll yields in an upward direction to accommodate the increased thickness of the work and the bearing block 78 is raised, thereby, through the medium of the pin 77 depressing the long arm of the lever 76 to move the wedge-block 70 downwardly; which action, because of the wedge shape of the block, causes the napping roll to be moved a very slight distance away from the work, in fact, a distance equal to the increased thickness of the work, so that the depth of penetration into the work and the depth of the nap raised remains the same for various thicknesses of work. It will be observed that the machine automatically adjusts itself to various thicknesses of work after it has been set to raise the nap a predetermined depth, but the depth of nap raised may be changed at any time by manipulation of the pin 80.

Although my invention is illustrated as applied to a machine adapted for raising the nap on laundered blankets, it is to be understood that it is not limited to such machines, because the invention is capable of use generally in brushing, combing, and other similar varieties of machines, nor is it my intention to limit it to a machine in which the napping roll travels in the same direction as the work. Furthermore, the invention is not to be limited to automatic means for regulating the position of the napping roll, since in some machines it may be found useful to use the floating roll alone, held in position with or without weights by the force of gravity. This may be found especially advantageous in a machine used for raising nap of little depth upon comparatively hard fabrics.

What I claim is:—

1. In a machine of the character described, the combination with means for feeding the work of a floating roll for raising the nap on the work and means controlled by said feeding means for varying the position of said roll in accordance with the thickness of the work. 70

2. In a machine of the character described, the combination with means for feeding the work of a fixed element over which the work is fed, a floating brushing roll held by gravity against the work as it is fed over said fixed element and means controlled by said feeding means for varying the position of said roll in relation to said work in accordance with the thickness of said work. 75 80

3. In a machine of the character described, the combination with means for feeding the work of a pivotally suspended floating roll adapted to be held against the work by gravity as it is fed forward and means for rotating said roll at a speed greater than the speed of the work. 85 90

4. In a machine of the character described, the combination with means for feeding the work of a pivotally suspended brushing roll adapted to be held against the work by gravity and means for rotating said roll in the same direction and at a speed greater than the speed of the work. 95

5. In a machine of the character described, the combination of a pair of feed rolls for feeding the work, a fixed element over which the work is fed, a pivotally suspended floating brushing roll held by gravity against the work as it is fed over said fixed element and means for rotating said roll in the same direction as the feed of the work, but at a greater speed. 100 105

6. In a machine of the character described, the combination of a pair of feed rolls for feeding the work, a pivotally suspended floating brushing roll, means for holding said roll against the work by gravity, and means for limiting the approach of said roll to the work, said means being controlled by the said feed rolls in accordance with the thickness of the work. 110 115

7. In a machine of the character described, the combination of means for feeding the work, a floating brushing roll hung pivotally, means for holding said roll toward the work, said means being operated by gravity, and means for limiting the approach of said roll to the work; said limiting means being operated by the feeding means in accordance with the varying thickness of the work. 120 125

8. In a machine of the character described, the combination of a pair of feed rolls for feeding the work, one of said rolls being free to yield to accommodate work of varying thicknesses, a floating roll for 130

- raising the nap on the work, said roll being hung off center whereby it is forced toward the work by gravity, means for limiting its movement toward the work, said 5 means being adjustable to regulate the distance between the work and the roll and means whereby said adjustable limiting means is operated automatically according to the varying thickness of the work.
- 10 9. In a machine of the character described, the combination of a pair of feed-rolls for feeding the work, one of said rolls being free to yield to accommodate work of varying thickness, a floating roll for raising the nap on the work, said roll being hung off center whereby it is forced toward the work by gravity, means for limiting its movement toward the work, said means being adjustable to regulate the distance 15 between the work and the roll and means operated by said feed-rolls whereby said adjustable limiting means is operated automatically accordingly to the varying thickness of the work.
- 20 10. In a machine of the character described, the combination of a pair of feed-rolls for feeding the work, one of said rolls being yielding to accommodate work of varying thickness, a napping roll pivotally mounted off center, means for holding the roll toward the work, means intermediate said feed-rolls and said napping roll for adjusting the relation of said napping roll to the work in accordance with the 25 varying thickness of the work.
- 30 11. In a machine of the character described, the combination of means for feeding the work, a napping roll pivotally hung off center and adapted to be forced against the work by gravity and means controlled by said feeding means for adjusting the approach of said napping roll to the work in accordance with the varying thickness of the work.
- 35 12. In a machine of the character described, the combination of an idler roll, means for feeding the work over said idler roll, a napping roll pivotally suspended in hangers slightly off center to cause it to engage laterally the work on said idler roll, means on said hangers for carrying weights to vary the pressure exerted on the work by said napping roll and means for rotating said napping roll.
- 40 13. In a machine of the character described, the combination of an idler roll, means for feeding the work over said idler roll, a napping roll pivotally suspended in hangers slightly off center to cause it to engage laterally the work on said idler roll, a rearwardly extending arm on each hanger for receiving weights to vary the pressure exerted on the work by said napping roll and means for rotating said napping roll.
- 45 14. In a machine of the character described, the combination of a pair of feed-rolls for feeding the work, one of said rolls being free to yield to accommodate work of varying thicknesses, a napping roll for raising the nap on the work, said roll being hung off center whereby it is forced toward the work by gravity, a wedge-block vertically movable for regulating the position of said napping roll with relation to the work and means whereby said wedge-block is moved vertically by the vertical movement of said free feed-roll.
- 50 15. In a machine of the character described, the combination of a pair of feed-rolls for feeding the work, one of said rolls being movable to accommodate work of various thicknesses, a napping roll movable toward and from the work, means for normally pressing said napping roll toward the work and means actuated by the movement of said movable feed-roll for adjusting the relation of said napping roll to the work.
- 55 16. In a machine of the character described, the combination of a pair of feed-rolls for feeding the work, one of said rolls being movable to accommodate work of various thicknesses, a napping roll movable toward and from the work, means for normally pressing said napping roll toward the work, a wedge-block intermediate said feeding means and said napping roll and movable vertically for regulating the relation of said napping roll to the work and means whereby said wedge-block is actuated by the movable feed-roll in accordance with the varying thickness of the work.
- 60 17. In a machine of the character described, the combination of means for feeding the work, a napping roll movable toward and from the work, means for normally pressing said napping roll toward the work and means controlled by the feeding means for varying the relation of said napping roll to the work in accordance with the thickness of the work.
- 65 18. In a machine of the character described, the combination of means for feeding the work, a napping roll movable toward and from the work, means for normally pressing said napping roll toward the work, means intermediate said feeding means and said napping roll and movable for regulating the relation of said napping roll to the work and means whereby said intermediate means is actuated by the feeding means in accordance with the varying thickness of the work.
- 70 19. In a machine of the character described, the combination of a pair of co-operating feed-rolls for feeding the work, one of said rolls being free to move to accommodate various thicknesses of work, a pivotally suspended napping roll movable toward and from the work, a wedge-block intermediate said feed rolls and said nap-

ping roll, said block being vertically movable to regulate the relation of said napping roll to the work and connections between said wedge-block and said movable feed-roll for moving said wedge-block vertically in accordance with the vertical movement of said movable feed-roll.

20. In a machine of the character described, the combination with means for

feeding the work of a floating brushing roll, means for controlling the relation of the said brushing roll to the work and means in engagement with the work for operating said controlling means in accordance with variations in the thickness of the work.

In witness whereof, I hereunto set my hand this sixteenth day of December, 1924.

RICHARD H. MONK
